UNITED STATES PATENT OFFICE.

JAMES A. BYRON, OF CARRIZOZO, NEW MEXICO.

GEAR MECHANISM FOR WINDMILLS.

1,248,261.

Specification of Letters Patent. Patented Nov. 27, 1917.

Application filed August 16, 1915. Serial No. 45,759.

To all whom it may concern:

Be it known that I, JAMES A. BYRON, a citizen of the United States, residing at Carrizozo, in the county of Lincoln and State 5 of New Mexico, have invented a new and useful Gear Mechanism for Windmills; and I do hereby declare the following to be a full, clear, and exact description of the invention, such as will enable others skilled in 10 the art to which it appertains to make and use the same.

This invention relates to improved gear mechanism including a wheel or revoluble beam having the blade thereon adjustable, 15 so that the arc on which the blades travel may be increased or decreased, by adjusting the blade on the revoluble beam, so that the pump rod will be operated at different speeds, according to different depths of 20 wells.

One of the features of the invention is the provision of a casting capable of horizontal oscillation, and in which casting a shaft is mounted having a crank arm at 25 one end and the vertical revoluble beam at the other end there being a link connecting said crank arm, and adjustably connecting a segmental gear, which in turn operates a rack, to which the pump rod is connected. 30 By virtue of the adjustable connection of the link to the segmental gear, a longer or shorter stroke may be imparted to the pump rod, according to the different depths of wells and the like.

35 In practical fields the details of construction may necessitate alterations, falling within the scope of what is claimed.

The invention comprises further features and combination of parts, as hereinafter set 40 forth, shown in the drawings and claimed.

In the drawings:—

Figure 1 is a view of the improved gear mechanism constructed in accordance with the invention.

45 Fig. 2 is a view in elevation, showing the blade of the revoluble beam adjusted in other positions, and showing the link connected to the segment gear in another position.

50 Fig. 3 is a sectional view.

Fig. 4 is a detail view.

Referring to the drawings, 1 designates a portion of the tower of a windmill, which comprises the standards or posts 2, which 55 are secured at 3 to the member 4, in which the sleeve or bearing 5 rotates. The sleeve

or bearing 5 is carried by the casting 6 having a turn table 7. The turn table 7 is mounted upon anti-frictional members 8, which are located between the turn table 60 and the member 4, so that the turn table will oscillate horizontally easily. Rising upwardly from the side of the turn table is a lug or pin 9, on which an elbow 10 is mounted. Threaded at 11 in one of the tubular arms of the elbow is a laterally extending rod 12, to which, as shown a tail vane 13 is secured by the straps 14 and bolts or screws 15. A set screw 16 is designed to be adjusted to bite into the threads of the rod 70 12 to prevent the same from turning. A rod or wire 17 connects to the casting 6 and to the rod 12, thereby preventing the same from sagging. Connected at 18 to opposite sides of the rod 12 are the ends of the 75 coil springs 19, which coil springs extend toward the casting 6 and at angles upon opposite sides of the rod 12, and have their other ends in turn connected at 20 to the casting 6, so as to hold the vane and the rod 80 12 yieldably and laterally with relation to the casting. The casting 6 is provided with a pair of upwardly extending arms 21 and 22, and mounted in a bearing 23 of the arm 21 is a shaft 24, one end of which has a 85 sleeve 25, in which the beam 26 is secured adjustably, as shown at 27, and is designed to rotate or move with the shaft 24. The other end of the shaft 24 has a crank arm 28. Mounted upon the stub shaft or pin 30 90 is a segmental gear 31, the teeth of which mesh with the teeth of the rack 33. This rack in cross section is rectangular, and extends through the casting and the sleeve or bearing 5, in order to be reciprocated in the 95 casing and said sleeve, and while reciprocating it rotates with the casting and said sleeve. The segmental gear 31 has a plurality of apertures 34, through any one of which a suitable bolt or the like 35 extends, 100 for adjustably connecting one end of the link 36 to the segmental gear. The other end of the link 36 is pivotally connected at 37 to the arm 28 of the shaft 24, so that when the shaft 24 rotates, the crank arm 105 will impart movement to the link 36, which in turn will rock the segment gear on its pivot. The segmental gear when rocked or oscillated, and owing to being in mesh with the rack 33, will impart a vertical reciprocating movement to the rack and the pump rod. By adjusting the link 36 with rela- 110

tion to the segmental gear, a longer or greater or shorter movement will be imparted to the gear, thereby increasing or decreasing the stroke of the rack and the pump rod, according to the different depth of wells. Carried by the end portion of the revoluble beam 26 are blades 39, which are adjustable upon the beam, by loosening and tightening the straps 40, which are secured 10 at 41 upon the blades 39. When the link 36 is connected to the segmental gear to impart the greatest oscillatory movement thereto, to increase the stroke of the rack and the pump rod, the blades 39 are adjusted further toward the outer extremities of the revoluble beam, in order to take care 15 of the increased stroke of the rack and pump rod. When the link is connected to the segmental gear for imparting a shorter 20 stroke to the rack and pump rod, the blades are adjusted toward the center of the revoluble beam.

The invention having been set forth, what is claimed as new and useful is:—

25 In a gear mechanism, a support having a horizontal bearing, a casting rockably mounted on said bearing, and provided with a device to be actuated, whereby the casting may rock on said bearing, means to limit

the movement of said casting, a reciprocating member movable through said casting, a pair of arms rising upwardly from the casting, one upon each side of the member, a vertically rocking segment carried by the upper extremity of one of said arms and being geared to said member, whereby said member is reciprocated through said casting at right angles to the plane of the rocking movement of the casting, the other arm having at its upper end a horizontally disposed bearing, a revoluble shaft in said last named horizontal bearing and having means at one end whereby revoluble movement may be imparted to said shaft, the other end of said shaft having a crank arm, and a pitman 45 connected at one end of the crank arm, and its other end provided with an adjustable pivotal connection with one end of said segment, whereby, variable movements may be imparted to the reciprocating member. 50

In testimony whereof I have signed my name to this specification in the presence of two subscribing witnesses.

JAMES A. BYRON.
